FORK OR SIMILAR ARTICLE

Stephen H. Berni, 673 Pelham Road,
New Rochelle, N.Y. 10022

Filed Feb. 11, 1970, Ser. No. 21,373

Term of patent 14 years

Int. Cl. D7—03

U.S. Cl. D54—12

FIG. 1 FIG. 2 FIG. 3

FIG. 1 is a top plan view of a fork or similar article showing my new design;

FIG. 2 is a side view of the fork of FIG. 1; and FIG. 3 is a bottom view of the fork of FIG. 1.

The design is intended for use on sets comprising forks, spoons, and knives and similar articles of flatware.

The essential features of my design reside in the handle portion as shown in the accompanying drawings.

I claim:

The ornamental design for a fork or similar article, as shown and described.
